UNITED STATES PATENT OFFICE

WILLIAM P. BEATTIE, OF NORWOOD, OHIO, ASSIGNOR TO THE AMERICAN LAUNDRY MACHINERY COMPANY, OF NORWOOD, OHIO, A CORPORATION OF OHIO

PRESSING MACHINE

Application filed October 9, 1925. Serial No. 61,483.

This invention relates to power actuated pressing machines such as are used for pressing garments or for ironing laundered articles.

5 The object of the invention is to provide an improved press of this kind in which the head is lowered manually into pressing relation with the bed, following which ironing pressure may be produced by power actuated means.

10 Further objects of the invention are to provide an improved press of the kind described in which the operating connections from the power source to the pressing head are disabled when the press is open and continue so until the head has been manually moved so close to the bed as to avoid any possibility of any abnormal obstruction, such as a part of the operator's person, lying between the 15 head and bed, thereby safeguarding the operator from injury, and in which, moreover, when the press has been manually closed said operating connections are rendered effective and are latched or held in operating position.

20 A further object of the invention is to provide means enabling the operator at will to unlatch said operating connections for opening the press without the production of power pressure.

25 A further object of the invention is to provide a press of this kind in which the head is opened by the power means and wherein the power mechanism automatically uncouples or disables the operating connections 30 after a power operation.

35 A further object of the invention is to provide suitable improved control and timing means for producing power sequence of the operating movements and for stopping the 40 head accurately in its several positions.

45 A further object of the invention is to provide a special form of operating connections from the power operating member to the pressing members and which mechanism is 50 specifically in the form of auxiliary toggle members capable of being broken to disable said connections or of being straightened to form a connecting rod between a power operating crank and the usual toggle operating members for the press head, and which aux-

iliary toggles are capable of being actuated both automatically and at will to produce or prevent operating relation or position thereof.

55 Further objects of the invention are in part obvious and in part will appear more in detail hereinafter.

In the drawings, which represent one suitable embodiment of the invention, Fig. 1 is a side elevation, partly in section on the line 11, Fig. 2, and showing the press open; Fig. 2 is a sectional plan view on approximately the line 2—2, Fig. 1; Fig. 3 is a sectional elevation on approximately the line 3—3, Fig. 2; Fig. 4 is a detail elevation of the timing switch with the casing cover removed; Fig. 5 is a sectional plan view thereof on approximately the line 5—5, Fig. 4; Fig. 6 is a detail sectional elevation on the line 6—6, Fig. 2, and illustrating the magnetically controlled 60 brake and a circuit switch; Fig. 7 is a detail sectional elevation on the line 7—7, Fig. 1; and Fig. 8 is an electric diagram.

70 The machine shown in the drawings comprises a suitable frame 1 supporting the usual padded garment support or pressing bed 2 and provided with an upwardly extending rear portion 3 on which is pivoted the upper lever 4 carrying the heated pressing head 5 and provided with an operating handle 6 at its forward end and with a counterweight 7 on its rear arm. Said counter-weight is so adjusted as to always tend to open the pressing members. For operating them the pressing members are connected to a pair of upper 75 and lower toggle members, the lower toggle member 8 being pivoted at 9 to the stationary frame and being provided with a foot 10 adapted to engage a stationary abutment 11 and limit press opening movement, and being 80

85 pivotally connected at its upper end to the knuckle pin 12 connecting it to a rod 13 forming the upper toggle member. Said rod slides in a swivel block 14 carried by the head lever 4 and is provided with an adjustable collar 15 forming an abutment to 90 vary the pressure of a compression spring 16.

95 The pressing members are operated by any suitable power operating prime mover, such as the electric motor 17, the shaft 18 of which 100

is provided with a brake drum 19, beyond which said shaft extends into a casing 20 and is there provided with a worm 21 on shaft 18 connected to drive a worm wheel 22 on a shaft 23, which latter shaft is provided with a crank 24 connected by a connecting rod to the toggle knuckle 12.

The connecting rod includes two members pivotally connected together by the pin 25, the first of such members, marked 26, extending from said pin to the end of the crank 24 and the second of said members, marked 27, extending from the pin 25 to the toggle knuckle 12. Said members 26, 27 are provided with abutments 28, 29 (Fig. 3) adapted 15 to engage each other when the auxiliary toggle formed by members 26, 27 is moved to or a little beyond straightened position, as shown in full lines, Fig. 3, and one of said 20 abutments, and particularly the abutment 29, is provided with a laterally extending pin on which is a roller 30, (Fig. 2) adapted to engage the hub of the crank 24 during operation of the parts for the purpose of breaking or 25 opening the auxiliary toggle, as will appear. 31 represents a foot treadle pivoted at 32 in the frame and normally pressed against its stop 33 by a tension spring 34. The rear arm of said treadle has an upwardly extending 30 portion terminating in a lateral extension 35 lying beneath the auxiliary toggle members when straightened, as shown in full lines, Fig. 3, to enable the operator to break or open the same at will and enable the pressing members 35 when closed to be restored to open position prior to and without the application of power pressure.

The brake drum 19 is utilized for the purpose of stopping the moving power operating parts, for which purpose it cooperates with 40 a brake band 36 fixed at 37 to a stationary part and at its opposite end connected to a rod 38 provided with a collar 39 forming an abutment for the compression spring 40. Said 45 spring normally tends to tighten the brake band around its drum, but may be compressed to release the brake by the energization of a brake release coil 41 which actuates an armature 42, having an extension 43 carrying an adjustable abutment screw 44 opposite the end of rod 38. A lateral extension 45 on the armature 42 supports a yielding contact 46 adapted when the coil 41 is energized to be moved into conducting relation 55 with a contact 47.

The timing switch includes members located within a hollow casing 48 surrounding the shaft 23 and fixed against rotation by a bolt 49 extending from the casing 48 to a part 60 of the stationary frame, such as the casing 20. In said casing 48 the shaft 23 is provided with an insulating drum 50 provided with two conducting segments 51, 52 cross connected by a bridge 53 and provided with 65 gaps 54 located side by side. The segment 51

cooperates with two yielding contact members 55, 56 and the segment 52 with two like yielding contact members 57, 58. All of the four contact members 55, 56, 57 and 58 are mounted upon stud shafts 59 adjustable circumferentially of the shaft 23 in slots 60 in the wall of casing 48, as shown in Figs. 4 and 5, to enable the several contacts to be accurately timed with relation to their segments.

Referring to Fig. 8, 61 represents the main 75 line switch. 62 is the pressure button and 63 the release button, these two button switches being preferably mechanically cross-connected or interlocked, as shown, so that but one thereof can be pressed at a time, while 80 closing of one switch automatically opens the other.

The operation is as follows:

Fig. 1 shows the parts in full open position. The crank 24, it will be observed, has 85 rearward motion from its extreme right hand position in dotted lines, Fig. 3, to its extreme left hand position with the crank horizontal, and a forward motion from its said extreme left hand position back again, all motion being 90 in the clockwise direction. When the press is open, as in Figs. 1 and 2, the crank 24 is near, but short of the end of its rearward travel and the auxiliary toggle formed by members 26, 27 is open or broken, with the connecting pin 25 at approximately the position of shaft 23 and with the pin 30 riding on the hub of the crank. By grasping the handle 6 the head can be manually pulled down into close pressing relation with the 100 bed or to the end of the safe zone, which motion, if not obstructed, will move the parts to the full line position, Fig. 3, thereby straightening the auxiliary toggles 26, 27, until the abutments 28, 29 contact, and also 105 nearly straightening the main toggles 8, 13.

The parts are now ready for the power pressure operation, which will be later described, but if after closing the press to the end of the safe zone, as described, the operator desires to immediately open it without a power pressure operation he may do so by depressing the foot treadle 31 and causing its lateral extension 35 to move upwardly and break the auxiliary toggle 26, 27, enabling 110 the head to be raised either by the hand or by the effect of its counter weight.

When the operator desires a power pressure effect with the parts in the position shown in full lines, Fig. 3, to wit, with the head 115 closed to the end of the safe zone, he depresses the pressure button 62, Fig. 8, thereby completing a circuit from L1 by way of button 62, wire 64, contact 55, segment 51, bridge 53, segment 52, contact 57, wire 65, brake 120 release coil 41 and wire 66 to L2. Energization of the coil 41 releases the brake and also closes the switch contacts 46, 47 which completes a circuit from L1 through contacts 46, 47 and through the motor armature and field 125 130

to L2. The motor therefore starts and rotates the crank from the position shown in full lines, Fig. 3, about 45 degrees to a position in which the crank 24 is substantially horizontal and at the left of shaft 23. In this position the gaps in the segments 51, 52 reach the contacts 55, 57 and the opposite ends of the segments engage the contacts 56, 58. Opening of the circuit through the contacts 55, 57 de-energizes coil 41, whereupon the 10 brake is applied by the spring 40 and contacts 46, 47 open, breaking the motor circuit. The motor operated parts therefore stop with the pressing members in full pressing position.

To open the press after any desired period of pressing, the operator depresses the pressure release button 63, thereby establishing another starting circuit from L1 through said 20 button by way of contact 56, segments 51, 52 and contact 58, to wire 65, coil 41, etc., thereby again releasing the brake and completing the motor circuit through contacts 46, 47. The motor thereupon starts and rotates the crank 24 in the clockwise direction. During this forward motion of the crank 24 from left to right in Fig. 3, the auxiliary toggle including members 26, 27, functions as a tension member to positively pull open the main toggles 25 8, 13, so continuing until approximately the dot-dash line position, Fig. 3, is reached, whereupon the roller 30 engages the hub of the crank 24 and stops further lowering movement of the auxiliary toggle member 27, but 30 crank 24 and toggle member 26 continue to rotate in the clockwise direction. The effect is to automatically break or open the auxiliary toggle members 26, 27, the parts moving to the position shown in Fig. 1, where the 35 segments 51, 52 leave or pass beyond the contacts 56, 58 and de-energize and open the circuit through the coil 41, resulting in immediate stopping action of the motor operated parts and application of the brake. The parts 40 have now been restored to their original positions, ready for another manual closing operation to be followed by a power pressure operation, as before.

The foregoing describes normal operation 45 when the closing of the pressing members is not obstructed. Under emergency conditions, such as when the operator's hand or arm accidentally lies between the pressing members, their full closure by manual operation is prevented, so that the auxiliary toggle members 26, 27 do not move to full straightened position, but to a position short thereof. Therefore, even though the power pressure button 62 be depressed to cause the motor to 50 proceed through a power pressure cycle the power effect of crank 24 is not transmitted through toggle members 26, 27 to the main toggles, but the auxiliary toggle is further opened or broken and a power effect is not 55 produced. Likewise, if the pressure button

62 is depressed with the press in open position, as in Fig. 1, the crank 24 proceeds through its power operation and the pin connecting it to member 26 engages member 27 and elevates the same, so that by depressing the release button 63 the crank 24 may be made to continue through a release operation to restore the parts to original position, all without the production of any power effect upon the press members.

The press described is safe in that it is impossible to produce the application of power effect to the head lever at any time other than when the pressing members are closed to the end of the safe zone and consequently 70 at a time when it is impossible for a part of the operator's person to be in a dangerous position between the pressing members. The operating connections between the power operating member, to wit, crank 24, and the 75 main toggle members is of a character adapted to be either disabled from producing closing or pressing operations or rendered effective therefor, but, of course, is always effective to open the press when closed. Under 80 ordinary circumstances, such operating connections are rendered effective for pressure operation by closing movement of the press and are automatically disabled during the release operation after the press is opened. At 85 the same time said connections may be disabled at the will of the operator after the press has been closed, but prior to the production of a power pressure effect.

What I claim is:

1. A pressing machine, comprising relatively movable pressing members, main toggle members for producing relative movement of said pressing members to thereby close and open the press, auxiliary toggle 105 members connected at one end to a point between the ends of said main toggle members, said main toggle members being manually operable to effect closing of the press, and a movable member supporting and connected 110 to the other end of said auxiliary toggle members for operating the same and being unaffected by the closing of the press.

2. A pressing machine, comprising relatively movable pressing members, main toggle members for producing relative movement of said pressing members to thereby close and open the press, auxiliary toggle members connected at one end to a point between the ends of said main toggle members, said main toggle members being manually operable to effect closing of the press, and a rotatable member supporting and connected 115 to the other end of said auxiliary toggle members for operating the same and being unaffected by the closing of the press.

3. A pressing machine, comprising relatively movable pressing members, main toggle members for producing relative move-

ment of said pressing members to thereby close and open the press, said main toggle members being manually operable to close the press, a movable operating member, auxiliary toggle members connected at one end to a movable part of said operating member and at the other end to said main toggle members, and an abutment arranged to be engaged by said auxiliary toggle members insuring press opening operation of said operating member whereby said operating member is effective to break said auxiliary toggle members but ineffective to straighten them.

15. 4. A pressing machine, comprising relatively movable pressing members, main toggle members for producing relative movement of said pressing members to thereby close and open the press, said main toggle members being manually operable to close the press, an operating member, auxiliary toggle members connecting said operating member and said main toggle members, said auxiliary toggle members being moved to substantially straightened position by the closing of the press, and means carried by said auxiliary toggle members and co-operating with said operating member for breaking said auxiliary toggle members upon movement of said operating member.

35. 5. A pressing machine, comprising relatively movable pressing members, main toggle members for producing relative movement of said pressing members to thereby effect closing and opening of the press, said main toggle members being manually operable to close the press, auxiliary toggle members connected to said main toggle members and movable to substantially straightened position by closing of the press, a member connected to said auxiliary toggle members for effecting opening of the press, and means carried by said auxiliary toggle members and cooperating with said operating member to effect breaking of the auxiliary toggle members when the press is opened.

50. 6. A pressing machine, comprising relatively movable pressing members, main toggle members for producing relative movement of said pressing members to thereby effect closing and opening of the press, said main toggle members being manually operable to close the press, auxiliary toggle members connected to said main toggle members and movable to substantially straightened position by closing of the press, a member connected to said auxiliary toggle members for effecting opening of the press, means carried by said auxiliary toggle members and cooperating with said operating member to effect breaking of the auxiliary toggle members when the press is opened, means tending to open the press when said auxiliary toggle members are broken, and operator op-

erable means for breaking said auxiliary toggle members.

In testimony whereof I hereby affix my signature.

WILLIAM P. BEATTIE.
